UNITED STATES PATENT OFFICE

WILLIAM P. FERGUSON, OF MIDDLEBURY, CONNECTICUT

DESIGN FOR A COMBINED VALVE CONTROL HANDLE AND INDEXING DIAL

Application filed August 16, 1932. Serial No. 44,615. Term of patent 3½ years.

To all whom it may concern:

Be it known that I, WILLIAM P. FERGUSON, a citizen of the United States, and residing at Middlebury, in the county of New Haven and State of Connecticut, have invented a new, original, and ornamental Design for Combined Valve Control Handle and Indexing Dial, of which the following is a specification, reference being had to the accompanying drawing, forming part thereof.

Fig. 1 is a perspective view of a combined

valve control handle and indexing dial, showing my new design.

Fig. 2 is a side elevational view of the same.

I claim:

The ornamental design for a combined valve control handle and indexing dial, as shown.

In testimony whereof, I have affixed my signature to this specification.

WILLIAM P. FERGUSON.
